(57) **CLAIM**

The ornamental design for a body for a floor cleaner, as shown and described.

DESCRIPTION

FIG. 1 is a front perspective view of a body for a floor cleaner showing our new design;

FIG. 2 is a rear perspective view thereof;

FIG. 3 is a left side view thereof;

FIG. 4 is a right side view thereof;

FIG. 5 is a front view thereof;

FIG. 6 is a rear view thereof; and,

FIG. 7 is a top view thereof.

The broken lines depict environmental subject matter that forms no part of the claimed design.
